ILLUMINABLE TRAFFIC SIGNAL OR
SIMILAR ARTICLE

James A. O'Neill, Chelsea, Mass.

Application February 2, 1953, Serial No. 23,390

Term of patent 14 years

(Cl. D72—1)

To all whom it may concern:

Be it known that I, James A. O'Neill, a citizen of the United States of America, residing in Chelsea, county of Suffolk, and State of Massachusetts, have invented a new, original, and ornamental Design for an Illuminable Traffic Signal or Similar Article, of which the following is a specification, reference being had to the accompanying drawing, forming a part thereof.

Fig. 1 is a front elevational view of an illuminable traffic signal showing my new design;

Fig. 2 is a side elevational view thereof;

Fig. 3 is a top plan view;

Fig. 4 is a cross-sectional view taken on the line 4—4 of Fig. 1; and

Fig. 5 is a cross-sectional view taken on the line 5—5 of Fig. 1.

The drawing is lined to show contrasting colors and the dominant features of my design are shown in solid lines.

I claim:

The ornamental design for an illuminable traffic signal or similar article, substantially as shown and described.

JAMES A. O'NEILL.
